UNITED STATES PATENT OFFICE

EDWARD D. BRANDT, OF SAGINAW, MICHIGAN.

ADJUSTABLE SHADE AND CURTAIN BRACKET.

Application filed November 17, 1923. Serial No. 675,353.

To all whom it may concern:

Be it known that I, EDWARD D. BRANDT, a citizen of the United States, residing at Saginaw, in the county of Saginaw and State of Michigan, have invented certain new and useful Improvements in an Adjustable Shade and Curtain Bracket; and I do hereby declare the following to be a full, clear, and exact description of the invention, such as will enable others skilled in the art to which it appertains to make and use the same.

This invention relates to adjustable and combined shade and curtain brackets and has for its object to provide a device of the character stated which is of generally improved construction and in which provision is made for the attaching of the bracket to window frames of different dimensions without the employment of screws or other fastening means of like kind which split and mar the woodwork of the window frame and through the employment of which it is difficult to secure a shade and curtain bracket in proper position.

A further object of the invention is the provision of a bracket having the above stated characteristics and which embodies means providing for the adjustment of the curtain pole or support and the shade roller supports simultaneously and also includes means providing for the adjustment of the shade roller supports independent of each other and independent of adjustment of the curtain pole or support, improved means being provided for securing the parts of the device in position after desired adjustments have been made.

A further object of the invention is to provide a device of the kind stated, which embodies a few number of parts, in which the desired adjustments may be readily and quickly made, and which is easily and cheaply constructed and may be manufactured and sold at a relatively low cost.

While the following description and accompanying drawings describe and illustrate the preferred embodiment of my invention, it is to be understood that minor changes in the construction, combination and arrangement of parts may be made without departing from the spirit and scope of the invention as claimed.

Referring to the accompanying drawings wherein like reference characters are applied to like parts in the different views,

Figure 1 is a front elevation of the upper portion of the window frame, showing my improved device attached thereto,

Figure 2 is a plan view of the device shown in Figure 1, the curtain support or pole being in place,

Figure 3 is a detail perspective view showing one of the curtain and shade roller supporting brackets detached,

Figure 4 is a detail sectional view showing the connection between the curtain pole and one of the supporting brackets,

Figure 5 is a sectional view showing the manner of securing the supporting brackets to the supporting rod or bar,

Figure 6 is a sectional view on the line 6—6 of Figure 1,

Figure 7 is an enlarged detail showing the improved locking means,

Figure 8 is a sectional detail of the locking means shown on the line 8—8 of Figure 7.

Referring in detail to the accompanying drawings, the device comprises essentially, a sectional supporting rod or bar 1, a sectional curtain supporting rod or pole 2, and the curtain pole and shade roller supporting brackets 3 one of which is disposed adjacent each end of the sectional supporting rod or bar 1. Each section of the supporting rod or bar, at its outer end carries one or more hooks 4 each having its end sharpened for penetration, and these hooks are designed to bite into the frame work of the window, to secure the device in place. The engagement of the hooks with the window frame is best shown in Figure 2. Secured adjacent each of the outer ends of the sections of the supporting bar or rod 1, is a small bar 5, each of these bars 5 having an opening or perforation adjacent each of its ends, whereby if found desirable screws or other fastening means may be passed through the openings to assist the hooks 4 in securing the improved device in place.

An elongated slot 6 is formed adjacent the outer ends of each of the sections of the supporting bar 1, and these slots provide for the adjustable mounting of the brackets 3 on the supporting bar. Each of the brackets 3 comprise, a base plate 7 having its longitudinal edges overturned to embrace the longitudinal edges of the respective sections of the supporting bar, and the brackets have one of their transverse edges bent to project forwardly and provide the ears 8

designed to receive a shade roller therebetween and support the same in the usual manner. The opposite transverse edges of the plates 7 are extended and reduced, and 5 bent to project forwardly of the plates and provide the outstanding lugs or projections 9 adapted to cooperate with each other to support the curtain pole 2.

Passing through the elongated slots 6 and

- 10 through the base or plate 7 of the brackets 3, are bolts 10 provided at their under sides with enlarged heads 11 and having a square sided portion adapted to fit within the slots and hold the bolts against rotation.
- 15 Threaded onto the outer ends of each of the bolts 10, is an enlarged disk 12 having its periphery extending beyond the longitudinal edges of the plates 7, so that the disk may be readily grasped and rotated to secure or loosen the brackets in place. The curtain pole or support, comprises a pair of sections 2^a and 2^b, each of which have their outer ends bent to extend rearwardly from their major portions and provided with ears 20
- 25 13 to be bent about the lugs or outstanding projections 9 of the brackets 3. The section 2^a of the curtain pole, has a bifurcated portion 13' adapted to be received within the hollow terminal portion 14 of the section 2^b.
- 30 A pin 15 passes through the hollow terminal portion of the section 2^b, and serves to hold the legs of the bifurcated portion of the section 2^a in spaced relation, to prevent the same becoming bent or distorted so as to interfere with their easy sliding movement in the section 2^b.
- 35

Means is provided for locking the sections 1^a and 1^b of the supporting bar 1, in their relative adjusted positions. To this end, 40 the section 1^a is provided with a plurality or aligned perforations 16, and is provided at its inner end with ears 17 to grip about the section 1^a and assist in holding the sections in close proximity one to the other. As 45 shown the sections are arranged side by side and adapted for longitudinal sliding movement to vary the length of the bar 1. The section 1^b, at its inner end has pivoted thereto a lever member 18, the pivot 19 being positioned inwardly of the end of the lever. At a point beneath the pivot 19, and at its rear side, the lever 18 carries a pin 20 50 adapted to be selectively engaged in one of the openings or perforations 16 in the section 1^a. Pivoted to the lever at a point outward of its pivotal connection with the section 1^a, is a catch member 20 adapted to cooperate with the outer twisted end 21 of the lever, to hold the sections of the supporting bar 1 in proper position when desired 55 adjustments have been made.

In applying the improved structure to a window frame, the device is adjusted to have the hooks 4 engage opposite edges of the frame, with the lever 18 thrown to the

left side of its pivot and having its pin 20 in engagement with one of the openings or perforations 16. In this position, when the lever is moved to the right hand side of its pivot, it draws the sections 1^a and 1^b toward each other and causes the hooks 4 to bite into the frame work and secure the supporting bar and parts carried thereby in proper position.

Having thus described the invention, what I claim is:—

1. In a device of the class described, a supporting bar including a pair of longitudinally adjustable sections each of said sections having an elongated longitudinally extending slot adjacent its outer end, means passing through each of said slots and adjustable therein, a bracket secured to each of said means adjustable therewith, each of said brackets comprising a plate having its ends bent forwardly to provide means for supporting a shade roller and means for supporting a curtain pole, means associated with the first named means to secure the latter and the brackets in required adjusted position, and means associated with the supporting bar to secure the sections thereof in required adjusted position.

2. In a device of the class described, a supporting bar including a pair of longitudinally adjustable sections, each of said sections having an elongated longitudinally extending slot adjacent its outer end, means passing through each of said slots and adjustable therein, a bracket secured to each of said means and adjustable therewith, each of said brackets provided with means for supporting a shade roller and other means for supporting a curtain pole, and means associated with the first named means to secure the latter and the brackets in required adjusted positions.

3. In a device of the class described, a supporting bar including a pair of longitudinally adjustable sections, a bracket secured to each of said sections adjacent its outer end, said brackets provided with means for supporting a shade roller and other means for supporting a curtain pole, and means associated with the supporting bar to secure the sections thereof in required adjusted position, said last named means comprising a lever pivoted inwardly of one end thereof to one of the sections of said supporting bar and having a pin selectively engageable in one of a series of openings in the other of said bars, and adapted to be rocked to draw the outer ends of said sections toward each other, said lever having its free end bent to clampingly engage that section of the supporting bar provided with the opening, whereby to prevent separation of said sections.

In testimony whereof I affix my signature.
EDWARD D. BRANDT.
